UNITED STATES PATENT OFFICE.

HANS P. HANSEN, OF CHICAGO, ILLINOIS, ASSIGNOR TO CHICAGO CYCLE SUPPLY COMPANY, OF CHICAGO, ILLINOIS, A CORPORATION OF ILLINOIS.

DESIGN FOR A TIRE.

45,932.

Specification for Design. Patented June 16, 1914.

Application filed November 4, 1912. Serial No. 729,505. Term of patent 7 years.

To all whom it may concern:

Be it known that I, HANS P. HANSEN, a citizen of the United States, and a resident of the city of Chicago, county of Cook, and State of Illinois, have invented a new, original, and ornamental Design for Tires, of which the following is a specification, reference being had to the accompanying drawing, forming part thereof.

In the drawing:—Figure 1 is a plan view of the tread of a part of my novel tire design.

Fig. 2 is a side elevation of the same. Fig. 3 is a transverse section through the tire in a plane indicated by the line 3—3 of Fig. 2.

I claim:—

The ornamental design for a tire, as shown.

HANS P. HANSEN.
